CLAIM

The ornamental design for a shot shell loader for shotgun magazines, as shown and described.

DESCRIPTION

FIG. 1 is a perspective view of a shot shell loader for shotgun magazines;

FIG. 2 is an additional perspective view thereof;

FIG. 3 is a left side elevation view thereof, a right-side elevation view being a mirror image thereof;

FIG. 4 is a top plan view thereof;

FIG. 5 is a bottom plan view thereof;

FIG. 6 is a back view thereof; and,

FIG. 7 is a frontal view thereof.
